METHOD FOR PRESSING CORRUGATED CARDBOARD FLAT IN PLACES

Application filed April 18, 1928, Serial No. 270,998, and in Germany May 10, 1927.

When applying advertising matter in the form of pictures and letterpress to corrugated cardboard, various methods have hitherto been adopted. The places on the cardboard which are to be provided with the pictures and letterpress have been punched out and paper stuck behind them, which acted as a base for the pictures and letterpress to be stuck on. Another method has been to stick on the punched-out place a sheet with the required picture with a gummed strip.

According to the present invention the place intended to be used for the advertising matter is prepared by pressing the corrugations flat in the area in question, so that the sheet with the advertising matter can be stuck directly on the corrugated cardboard base. This has the disadvantage, that on the surface of the corrugated cardboard a fluting of the thickness of the paper remains which is caused by the corrugations laid over sideways by the die during the pressing operation, which have a disturbing effect more particularly when the sheet of advertising matter contains representations of figures. This drawback may be overcome, by the corrugated cardboard being pressed over a yielding foundation, whereby the completely flat upper surface is produced, as the folds causing the fluting can give way downwards, thus appearing only on the reverse side.

In the accompanying drawings Fig. 1 shows the first stage in the pressing operation and Fig. 2 the final stage of the pressing operation according to the present invention.

a is the lower sheet of paper of the corrugated cardboard which is substantially flat before the pressing operation and *b* the upper corrugated sheet of paper of the corrugated cardboard. At *c* is indicated how the corrugations of the upper sheet *b* in the first place are laid over flat on the pressing die, being applied and show a distinct fluting on the upper surface, the height of which corresponds at least to the thickness of the paper forming the corrugations laid over sideways by the pressing operation. *d* indicates a place which has been pressed flat in accordance with the invention and on which a sheet

e impressed with the picture or the like forming the advertisement is stuck.

The yielding base used in pressing consists of any suitable material for instance fine felt, which, while it is capable of withstanding the high pressure used in pressing is so yielding that during the pressing operation it yields to the downwardly forced fluting and is pressed right into it. The yielding base may also consist of superimposed sheets of blotting paper or of Klingerit which is a well known packing material used in stuffing boxes and the like. The base is either so elastic that the fluting formed in its working surface during each operation disappears again as soon as the pressure is released or the material, of which the base is made is so plastic that during a following operation the ribs left in the base from the previous operation disappear again and fresh depressions are formed in the base by the downwardly forced corrugations of the paper.

I claim:

A method for pressing corrugated cardboard flat in places which consists in supporting the cardboard on the reverse side and pressing it from the upper side to laterally lay over the corrugations on said upper side to shallow ribs corresponding in height to the thickness of the paper and to displace such shallow ribs during the pressing operation towards the yielding reverse side of the cardboard, thus producing a completely flat upper surface.

In testimony whereof I affix my signature. 85
LUDWIG CLEMENS.
